CLAIM

The ornamental design for a communication terminal, as shown and described.

DESCRIPTION

FIG. 1 is a front elevational view of a communication terminal showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front and right side perspective view thereof; and,

FIG. 8 is a bottom, rear and left side perspective view thereof.

The broken lines in the drawings illustrate portions of the communication terminal which form no part of the claimed design. The oblique shade lines in the drawings represent a reflective surface.
